UNITED STATES PATENT OFFICE.

ALEXANDER M. BELLONY, OF THE UNITED STATES ARMY.

WHEEL BLOCKING AND JACKING DEVICE.

1,398,534.

Specification of Letters Patent. Patented Nov. 29, 1921.

Application filed April 26, 1919. Serial No. 293,030.

(FILED UNDER THE ACT OF MARCH 3, 1883, 22 STAT. L., 625.)

To all whom it may concern:

Be it known that I, ALEXANDER M. BELLONY, captain, Corps of Engineers, United States Army, a citizen of the United States, 5 stationed at Washington, D. C., have invented an Improvement in Wheel Blocking and Jacking Devices, of which the following is a specification.

The invention described herein may be 10 used by the Government, or any of its officers or employes in prosecution of work for the Government, or by any other person in the United States, without payment of any royalty thereon.

15 The general object of my invention is to provide a novel "wheel blocking and jacking device" which shall be simple in construction, efficient in operation, and susceptible of application and removal with great celerity.

20 While my device may be used to advantage in connection with wheeled vehicles or machines generally, it is especially valuable for application to pile-driving machines, because it eliminates the necessity of taking 25 off the wheels of the pile-driving machine when the latter is in operation driving piles. By the use of my invention in connection with pile-driving machines there is no loss 30 of time in changing rollers, or in building a roller bed for moving the machine, and the time consumed in locking and releasing the wheels by my mechanism is reduced to a minimum.

The invention, broadly considered, resides 35 in pairs of complementary wheel blocking members, and in means for tightening and holding said members against the wheels of the machine.

The invention also resides in the combination, 40 with the structure noted in the preceding paragraph, of screw jacks carried by the wheel blocking members, or a portion thereof, for forcibly bearing against the under surface of the frame of the pile-driving machine, or the like, and forcing the wheel 45 blocks carrying said jacks forcibly against the ground, thus frictionally holding the wheel blocks and wheels against movement. Where the pile-driving machine is mounted 50 on a railroad flat car, or a floating barge, the frame of such machine may be elevated by the screwjacks.

The invention also resides in certain structural refinements, such as providing the 55 wheel-blocks with wheel-bearing surfaces,

curved in conformity with the contour of the wheels to which said blocks are applied, said refinements going to make up the ultimate perfection of the entire mechanism.

The invention is graphically illustrated in 60 the appended drawings, the several views of which may be briefly described as follows:

Figure 1 is a side elevation of a pile-driving machine (in skeleton outline), showing the application of my wheel blocking and 65 jacking mechanism thereto;

Fig. 2 is a top plan view, partly broken away, of said mechanism;

Fig. 3 is a vertical sectional view along the line 3-3, Fig. 2; and 70

Fig. 4 is a detail view in perspective, partly in section, of one of the wheel blocks.

Referring now, in detail to the drawings:

The wheel-blocking members preferably 75 comprise blocks 1, desirably of general rectangular shape, as shown. A pair of such blocks may be advantageously used for each wheel A of the object carrying such wheels, in this instance a pile-driving machine.

Advantageously, each of these blocks may 80 be recessed, as shown, for instance, very clearly in Fig. 4, to provide a downwardly inclined longitudinally cross-sectionally curved bearing-face bounded at the sides by vertical walls. The curvature of said bearing faces corresponds to the contour of the 85 peripheral portions of the wheel A.

Said recesses may be appropriately lined with metal or like wear resisting material, as shown at 2, said liner being, if desired, 90 provided with flanges 3, through which fastening means 4 may pass to secure the liner to the block.

Reinforcing means for each block may be provided, in this instance metal straps or 95 bands 5 encircling the blocks and secured thereto by appropriate means 6.

Extending transversely of the block from side to side thereof and on each side of said metal recesses are guide holes 7-7, which are 100 also advantageously metal lined, as shown at 8. The holes 7 of one of the blocks forming each pair may be of greater diameter for a portion of their length, as shown in Fig. 2 in respect to the block at the left hand 105 thereof. The metal liner of the holes may be provided with flanges 9 bent against the sides of said blocks and secured thereto by suitable fastening means.

Certain or all of said blocks may be pro- 110

vided with an aperture 10 therethrough extending at right angles to the guide holes 7, 7. A portion of said aperture 10 is of larger diameter, forming an annular shoulder 11 in the wall of said aperture intermediate the ends of the latter.

Projecting into said aperture 10 is a screw-jack barrel 12 resting at its bottom upon said shoulder 11, and provided with a 10 threaded bore, as shown, and with a head 13 which is secured by suitable fastening means 14 to the block 1.

Threaded into the bore of said screw-jack barrel is a screw-jack 15 carrying a 15 head 16 of appropriate shape to engage the frame of the machine. In this instance the head is shown provided with a diametric rib 16' on its upper surface, adapted to engage the frame channel bar B between the 20 depending flanges thereof.

Insertible through the holes 7 of one block of each pair are bolts 17 having at one end a hook 18 and having its other end threaded, on which may be screwed a nut 19, a washer 25 20 being interposed between said nut and the block 1.

The hook 18 of the bolt 17 engages the eye 21 at one end of a link 22 provided at its other end with a hook 23 engageable with 30 the eye 24 of a screw bolt 25 projecting through the hole 7 of the other block and carrying a collar 26 (see Fig. 2) adapted to be passed into the section of the hole having the larger diameter. The nut of the 35 screw bolt opposite the eye 24 is threaded, on which may be screwed a nut 27. Said nut is removably carried by a handle or lever 28, having, at one end, a yoke 29, into which may be threaded screws 30, whereby the 40 lever is secured to said nut.

In operation, one of said blocks is placed at each side of a wheel of the machine and the hooks 22 are thereupon coupled up with the screw bolts 25, and the levers 28 are 45 manipulated to tighten up the nuts 27 on the screw bolts 25, thereby tightening the blocks 1—1 against the wheel. The screw-

jack 15 is thereupon rotated until the head thereof firmly bears against the frame of the machine, thus forcing the block carrying said screw-jack with considerable pressure against the ground, thereby tending to prevent the blocks being dragged by the pile-driving machine, in the operation thereof.

The many advantages of my invention will be apparent, and will appeal especially to those skilled in the art to which the invention pertains. The mechanism comprises but few parts, which are not likely to get 60 out of order; the device is capable of being applied with great rapidity; and the mechanism, in operation, is exceedingly efficacious for the purpose intended.

Having thus fully described my invention, 65 what I claim as new and desire to secure by Letters Patent of the United States is:

1. A combined wheel blocking and jacking mechanism, comprising complemental, 70 slideable wheel engaging members disposable one on each side of a wheel, means for sliding said members toward each other and against the wheel, including a detachable coupling between the members, a screw jack barrel carried by one of said members and having a threaded bore and a screw jack threaded in said bore.

2. A combined wheel blocking and jacking mechanism, comprising complemental 75 wheel engaging members disposable one on each side of a wheel, means for sliding said members toward each other and against the wheel, including a detachable coupling between the members, a jack barrel carried by one of said members and a jack operable in 80 said barrel.

3. A combined wheel blocking and jacking mechanism, comprising complemental 85 wheel engaging members disposable one on each side of a wheel, means for sliding the members toward each other and against the wheel, a jack barrel carried by one of said members and a jack operable in said barrel.

ALEXANDER M. BELLONY.
